ABSTRACT OF THE DISCLOSURE

Dry cleaning and disinfecting compositions containing a saturated aliphatic dialdehyde of 2 to 10 carbon atoms as the disinfectant and method of using said compositions.

The invention relates to novel dry cleaning and disinfecting compositions and to a novel method of disinfecting textiles.

Recently, more attention than ever before is being given to the problem of thorough disinfection of woolen blankets, wearing apparel and various other textiles used in hospitals, community shelters and the like. An improvement in chemical disinfection is of great importance since known means have various defects. For example, fumigation of textiles with formaldehyde vapors is well known but this requires a step separate from the cleaning step and involves additional expense.

The simultaneous cleaning and disinfection of textiles has been found to be most advantageous and since a large number of textile materials cannot be washed in water, dry cleaning (with organic solvents) is the only practical means. Simultaneous dry cleaning and disinfection of textiles is known in which formaldehyde is added to the organic solvents as the disinfectant. However, the pungent odor of formaldehyde adheres to the textiles and a subsequent neutralization treatment in an ammonia bath is required to remove the odor. However, even with this subsequent treatment annoying odors cannot always be prevented from appearing later. Also, the subsequent treatment is disadvantageous because it requires additional time and a separate operation and subjects the textiles to greater wear and tear due to the mechanical stress.

It is an object of the invention to provide novel compositions for simultaneous dry cleaning and disinfecting of textiles.

It is another object of the invention to provide a novel method for the simultaneous dry cleaning and disinfecting of textiles which does not require any additional steps than normal dry cleaning.

These and other objects and advantages of the invention will become obvious from the following detailed description.

The compositions of the invention for the simultaneous dry cleaning and disinfecting of textiles are comprised of 0.1 to 5.0 grams, preferably 0.5 to 3.0 grams, of a saturated aliphatic dialdehyde of 2 to 10 carbon atoms per liter of a liquid organic dry cleaning solvent. The said compositions preferably contain 5 to 15 grams, preferably about 10 grams, of an anionic or non-ionic surface-active agent per liter of organic solvent to increase the cleansing power of the compositions.

The said compositions have the advantages of simultaneously cleaning and disinfecting textiles without trou-

2

blesome odors or other undesirable phenomena on subsequent treatments of the textiles such as the neutralization step required when formaldehyde is used in the organic solvent.

The saturated aliphatic dialdehydes used in the composition contain 2 to 10 carbon atoms, preferably 2 to 6 carbon atoms. Examples of suitable dialdehydes are glyoxal, malonic dialdehyde, succinic dialdehyde, glutaric dialdehyde, etc. Particularly preferred are glyoxal and glutaric dialdehyde.

If desired, the compositions may contain 0.1 to 0.3 gram, preferably about 0.2 gram, of formaldehyde per liter of the said compositions. These small amounts of formaldehyde do not cause any odors in the textiles treated with these compositions and less of the dialdehyde can be used.

Surface-active agents which are useful as cleaning assistants or boosters are well known. Examples of suitable agents are non-ionic surface-active agents such as alkylene oxide condensation products with high molecular weight fatty alcohols, amines, carboxylic acids and amides, alkylphenols, sugar esters and mixtures thereof and anionic surface-active agents such as soaps, fatty alcohol sulfates, alkane sulfonates, alkylaryl sulfonates, succinic acid ester sulfonates, fatty acid ester sulfonates, etc. When the surface-active agents are used, it is preferable to add small amounts of about 0.5 to 1.0 gram of water per liter of the said compositions. The compositions may also contain small amounts, i.e., 0.1 to 5.0 grams per liter of cationic agents such as high molecular weight amines and their salts such as thiouronium salts, alkylpyridinium bromides, etc.

Liquid organic solvents suitable for dry cleaning of textiles are well known and may be used alone or in mixtures. Examples of suitable solvents are chlorinated lower aliphatic hydrocarbons such as tetrachloroethylene, trichloroethylene, carbon tetrachloride, trifluoroethane, etc. and aromatic hydrocarbons such as benzene, benzol, light gasoline, heavy gasoline and their mixtures and saturated aliphatic hydrocarbons.

The textiles to be disinfected may be made of any synthetic or natural fiber such as rayon, Dacron, wool, linen, etc.

In the following examples there are described several preferred embodiments to illustrate the invention. However, it should be understood that the invention is not intended to be limited to the specific embodiments.

Example I

The bacteria lyophilized in skim milk were added to a cleaning solution which had been tempered at a temperature of 20° to 25° C. for suspension tests according to the directions for the testing of chemical disinfectants of Deutsche Gesellschaft fur Hygiene und Mikrobiologie (German Society for Hygiene and Microbiology) whereby bacterial counts 22×10^6 /ml. (*M. aureus*) and 3.2×10^6 /ml. (*Ps. aeruginosa*) were obtained. After calculated periods, bouillon was inoculated with this cleaning solution. The cleaning solution was perchloroethylene containing 10 gm. of a cleaning booster per liter and 0.1% of water and varying amounts of glutaric dialdehyde per liter. The cleaning booster consisted of 25% sodium dodecyl benzene sulfonate, 10% of the condensation product of 6 moles of ethylene oxide with one mole of nonylphenol, 55% naphtha and 10% isopropanol. It was then determined whether or not there was bacteria growth and the results are summarized in Table I.

+=Growth; (+)=Slight growth; ---No growth.

Example II

1 cm. square pieces of wool were sterilized in an autoclave and were then infected by placing them in bouillon cultures aged for 16 hours. After being dried overnight at 37° C., the wool pieces were placed in tempered dry cleaning baths in wide-neck flasks with ground-in stopper and thermometer. Magnetic stirrers were used to simulate

Germ counts of the inoculation suspensions:			
M. aureus	119×10 ⁸ /ml.		
E. coli	190×10 ⁸ /ml.		
Ps. aeruginosa	247×10 ⁸ /ml.		

5

Example III

1 cm. square pieces of wool were sterilized in an autoclave and then were impregnated with denser bacteria suspension for 15 minutes and dried overnight at 37° C. 10 The said pieces were placed in muslin bags and then cleaned in commercial dry cleaning equipment (Bowe R8) for 15 minutes and then were centrifuged for 3 minutes and dried in the usual manner. After cleaning and drying the bags were removed and the pieces of wool were inoculated in bouillon or placed on bouillon agar and covered with a thin layer of agar. After 8 days of incubation at 37° C., the number of sterile pieces of wool was determined. In one test, an additional 2.5 gm. 15 of dry bacteria lyophilized in skim milk were added directly to the cleaning solution which was the same as in Example I except for the dialdehyde. The results are summarized in Table III.

TABLE III

Glutaric dialdehyde, gm./l	Formaldehyde, gm./l	Bacteria										Wool impression on culture medium	Addition of dry germs to cleaning liquor	Program of cleaning			
		M. aureus			E. coli			Ps. aeruginosa									
		Inoculation suspension, per ml.	Bouillon	Bouillon agar	Inoculation suspension, per ml.	Bouillon	Bouillon agar	Inoculation suspension, per ml.	Bouillon	Bouillon agar							
0.5	----	78×10 ⁷	10/10	10/9	53×10 ⁸	10/10	10/10	202×10 ⁸	10/10	10/10	Sterile	M. aureus, 24×10 ⁸ . Ps. aeruginosa 14×10 ⁸ , per ml.	15 minutes in rotating drum.

-----	0.2	22×10 ⁸	10/0	10/0	37×10 ⁸	10/2	10/4	26×10 ⁸	10/0	10/1	-----	-----	8 minutes in rotating drum and 7 minutes in stationary drum.				

Number before/indicates number of test pieces of wool and number after/indicates the number of said pieces found to be sterile.

commercial dry cleaning conditions. After the woolen pieces had been in the bath for a specified time, they were removed, rinsed in petroleum ether for a short time, dried in air and placed in bouillon or on bouillon agar and covered with a thin layer of agar. The cleaning solution was the same as in Example I except the dialdehyde was glyoxal. The results are summarized in Table II.

Various modifications of the compositions and method of the invention may be made without departing from the spirit or scope thereof and it is to be understood that 55 the invention is to be limited only as defined in the appended claims.

I claim:

1. Compositions for simultaneous dry cleaning and disinfecting of textiles consisting essentially of 0.1 to 5.0

+=growth; ---no growth.

grams of a saturated dialdehyde of 2 to 10 carbon atoms per liter of a liquid organic dry cleaning solvent, selected from the group consisting of lower aliphatic hydrocarbons, aromatic hydrocarbons and saturated aliphatic hydrocarbons.

2. The compositions of claim 1 which contain 0.5 to 3.0 grams of the said dialdehyde.

3. The compositions of claim 1 wherein the dialdehyde is glutaric dialdehyde.

4. The composition of claim 1 wherein the dialdehyde is glyoxal.

5. The compositions of claim 1 which contain 0.1 to 0.3 grams of formaldehyde per liter of said solvent.

6. Compositions for simultaneous dry cleaning and disinfecting of textiles consisting essentially of 0.1 to 5.0 grams of a saturated dialdehyde of 2 to 10 carbon atoms and 5 to 15 grams of at least one surface-active agent selected from the group consisting of anionic surface-active agents and non-ionic surface-active agents per liter of a liquid organic dry cleaning solvent selected from the group consisting of lower aliphatic hydrocarbons, aromatic hydrocarbons and saturated aliphatic hydrocarbons selected from the group consisting of lower aliphatic hydrocarbons, aromatic hydrocarbons and saturated aliphatic hydrocarbons.

7. The compositions claim 6 which contain 0.5 to 1.0 grams of water per liter of said solvent.

8. The compositions of claim 6 wherein the dialdehyde is glutaric dialdehyde.

9. The compositions of claim 6 wherein the dialdehyde is glyoxal.

10. The compositions of claim 6 which contain 0.1 to 0.3 gram of formaldehyde per liter of said solvent.

11. A method of simultaneously dry cleaning and disinfecting textiles which comprises contacting the textiles with a composition consisting essentially of 0.1 to 5.0

grams of a saturated dialdehyde of 2 to 10 carbon atoms per liter of a liquid organic dry cleaning solvent selected from the group consisting of lower aliphatic hydrocarbons, aromatic hydrocarbons and saturated aliphatic hydrocarbons, removing the textile from the said composition and drying the textile.

12. The method of claim 11 wherein the dialdehyde is glutaric dialdehyde.

13. The method of claim 11 wherein the dialdehyde is glyoxal.

14. A method of simultaneously dry cleaning and disinfecting textiles which comprises contacting the textiles with a composition consisting essentially of 0.1 to 5.0 grams of a saturated dialdehyde of 2 to 10 carbon atoms and 5 to 15 grams of at least one surface-active agent selected from the group consisting of anionic surface-active agents and non-ionic surface-active agents per liter of a liquid organic dry cleaning solvent selected from the group consisting of lower aliphatic hydrocarbons, aromatic hydrocarbons and saturated aliphatic hydrocarbons removing the textile from the said composition and drying the textile.
